His Attorney.

UNITED STATES PATENT OFFICE.

ROBERT C. ROSS, OF WILMETTE, ILLINOIS, ASSIGNOR OF ONE-HALF TO SAMUEL SILVERMAN, OF CHICAGO, ILLINOIS.

ARCH-SUPPORT.

1,396,528.

Specification of Letters Patent.

Patented Nov. 8, 1921.

Application filed January 28, 1921. Serial No. 440,584.

To all whom it may concern:

Be it known that I, ROBERT C. Ross, a citizen of the United States, and a resident of the city of Wilmette, county of Cook, 5 and State of Illinois, have invented certain new and useful Improvements in Arch-Supports, of which the following is a specification.

My invention relates to new and useful 10 improvements in arch supports, and has for its object the provision of a metatarsal arch support which may be adjusted to suit feet of various sizes.

Other objects will appear hereinafter. 15 The invention consists in the combinations and arrangements of parts hereinafter described and claimed.

The invention will be best understood by 20 reference to the accompanying drawing forming a part of this specification, and in which,

Figure 1 is an inverted plan view, showing the metatarsal arch-engaging member mounted at its medial position upon the supporting plate;

Fig. 2 is a side elevation of a shoe on a smaller scale than Figs. 1 and 3 with parts broken away, showing the device in position in said shoe; and

Fig. 3 is a plan view, showing the member mounted in its shortened position upon the plate.

The form of invention illustrated in the drawing comprises a flexible member 6, 35 composed of leather or the like, upon which is rigidly mounted a main arch supporting plate 7 having an upwardly curved portion 8 on one side and bearing near one end a lug or pin 9 provided with an oblong head 40 10, and this pin is engageable by either one of a series of slots 11 provided in an oblong plate 12 which has a raised portion 13 at one end and a similar raised portion 14 at the other. These raised portions are made 45 of varying sizes as shown in the drawing.

The device is adjustable by means of the openings 11 which are placed at varying distances and either one of which may be engaged with the lug 9 to bring the raised 50 portions at the desired distance outward from the plate 7, in order to suit the particular size of the foot. The raised portions 13 and 14 are made of varying sizes so as to suit various sized metatarsal arches. This 55 device may be placed in position on the sole metatarsal arch.

15 of a shoe 16 as is shown in Fig. 2 and as is well understood.

If desired, the member 12 may be reversed upon the plate 7 bringing the raised portions 13 and 14 downward and thus providing a dished or depressed portion to engage the foot around a corn, callus, or the like, and protect the same.

While I have illustrated and described the preferred form of construction for carrying 65 my invention into effect, this is capable of variation and modification without departing from the spirit of the invention. I, therefore, do not wish to be limited to the precise details of the construction set forth, 70 but desire to avail myself of such variations and modifications as come within the scope of the appended claims.

Having described my invention, what I claim as new and desire to secure by Letters Patent, is:

1. An arch support comprising a supporting plate and a metatarsal arch-supporting member reversibly mounted on said plate.

2. A metatarsal arch support comprising 80 a flexible member, a supporting plate rigidly mounted thereon, an arch supporting member mounted on said plate and having an integral portion struck up from said member and longitudinally aligned openings, and 85 connecting means on said plate to engage one of said openings to adjust said member longitudinally and adapt the arch support to various sized feet.

3. An arch support comprising a foot-engaging member, a metatarsal arch-supporting member provided with various sized raised portions, and means to adjustably connect said members and adapt said arch support to various sized feet. 95

4. An arch support comprising a foot-engaging member, a metatarsal arch supporting member provided with a plurality of raised portions, and means on one of said members to engage the other member and cause either one or the other of said raised portions to engage the metatarsal arch. 100

5. A metatarsal arch support comprising a plate provided with a lug, a member adjustably mounted on said plate and provided 105 with openings to support said lug, and raised portions on said member either of which portions may, by means of said lug and openings, be caused to engage the metatarsal arch.

6. An arch support comprising a foot-engaging member, a metatarsal arch supporting member provided with raised portions, and mounting means on one of said members to engage the other member whereby the arch supporting member may be reversed on said foot-engaging member and also adjusted thereon for various sized feet.
7. An arch support comprising an arch supporting plate, a metatarsal arch supporting member having a raised portion on each

end thereof, and means to mount said member on said plate to cause either one of said portions to support the metatarsal arch and 15 the other to bear under the arch of the plate.

In testimony whereof I have signed my name to this specification in the presence of two subscribing witnesses.

ROBERT C. ROSS.
